UNITED STATES PATENT OFFICE

STANLEY L. CONNELL, OF GIRARD, PENNSYLVANIA, ASSIGNEE TO THE GIRARD MODEL WORKS, INC., OF GIRARD, PENNSYLVANIA, A CORPORATION OF PENNSYLVANIA

REGISTERING BANK

Application filed March 30, 1928. Serial No. 265,389.

This invention relates to coin registering banks, and has special reference to the provision of coin receiving receptacles adapted to register coins deposited therein and to visibly exhibit the total amount of the deposited coins.

The principal objects of the present invention include the provision of an improved coin registering mechanism for savings banks or the like, constructed and designed to register the size of coins of different denominations and to exhibit the totals of all of the coins of the different denominations deposited in the bank; the further provision of a coin registering mechanism operating upon a coin received by a stationary chute and fixedly positioned in such chute and operated by such positioned coin for actuating a registering element such as a registering wheel; the still further provision of a coin registering apparatus of this character designed for use with and for selective operation by coins of different sizes or denominations, the principle or mode of operation being such as to permit the use of a simplified construction of parts effectively organized in accordance with simple laws of coordination.

A still further prime object of the invention relates to the provision of a savings bank having different compartments for a "savings" account and a "spending" account, the savings compartment being normally inaccessible, while the spending compartment being always readily accessible for containing loose change and the like.

To the accomplishment of the foregoing and such other objects as will hereinafter appear, my invention consists in the elements and their relation one to the other, as are hereinafter more particularly described and sought to be defined in the claims, reference being had to the accompanying drawings which show the preferred embodiment of my invention, and in which:

15 Fig. 1 is a perspective view of the registering savings bank of the invention,

Fig. 2 is a view thereof taken on an enlarged scale and in cross section in the plane of the line 2—2, Fig. 1, with parts of the 50 operating mechanism broken away,

Fig. 3 is a perspective view of the operating parts of the registering mechanism of the bank,

Fig. 4 is a detail view of certain parts thereof,

Fig. 5 is a view taken in cross section in the plane of the line 5—5, Fig. 2,

Fig. 6 is a rear elevational view thereof with the rear wall of the casing removed.

Fig. 7 is a fragmentary view taken in cross section in the plane of the broken lines 7—7, Fig. 5, showing the operation of the registering mechanism with a coin of a given denomination, and

Fig. 8 is a view taken in cross section in the plane of the lines 8—8, Fig. 5 showing the operation of the registering mechanism with a coin of a different denomination.

Referring now more in detail to the drawings, the registering savings bank of the invention comprises a receptacle or casing A designed preferably to simulate a cash register and a coin receiving and registering mechanism generally designated as B housed or encased by said casing A, the said casing 70 A having a compartment C for receiving the coins deposited in and registered by the savings bank, the said casing being further provided with a separate compartment D in the form of a drawer independent of the registering mechanism B for receiving or holding loose change or coins, the compartment C thus forming a receptacle for "savings" and the compartment D forming an independent receptacle for "spending" money.

The casing or enclosure A may be made of sheet material bent and shaped to form the enclosing walls of the casing, which walls may be secured together in any desired way as by means of tongue and groove joints such as 10, 10. The top wall of said casing is provided with a plurality of slots 11, 12 and 13 for receiving a coin of desired denomination, such as a nickel, a dime or a quarter, respectively; and the front wall of the casing is provided with the sight windows 14 and 15 for the dials of the counting train of the registering mechanism and with an elongated slit 16 forming a guide means for the operating arm 17 of the registering mecha-

nism. The front wall of the casing at its bottom is provided with an opening 18 for the drawer 19; and the said casing is provided interiorly with a partition 20 which 5 separates the interior into the savings compartment C and the extra or spending compartment D. A side wall of the casing A is also provided with a door or closure 21 which is normally locked and which may be 10 opened by a key, or may be automatically opened after a given amount of money has been deposited in said bank.

The registering mechanism B of the invention embodies a construction or apparatus to receive and fixedly position a deposited coin and to be actuated by such fixed coin for imparting predetermined movements to the registering elements or wheels of the registering mechanism, the construction being such 15 that the coin does not form a connecting medium between the operating and the operated elements of the registering mechanism, and hence does not partake of the movements of such elements. In its broader aspects this 20 registering mechanism comprises a stationary coin chute generally and collectively designated as 22 adapted to receive a coin and to hold the same in a fixed position, an operated element such as a registering wheel 23, an operating element 24 normally unconnected to said registering element 23, and means such as any one of the devices 25, 26 25 and 27 movable into engagement with a coin deposited in the chute 22, said means being 30 constructed and arranged so as to be actuated by its engagement with the deposited coin for causing the operating element 24 to become operatively connected to said registering element 23 for driving the registering element, the amount or degree of movement 35 thereof being determined by the size or the denomination of the deposited coin.

In the preferred construction the savings bank is designed to receive and register coins 40 of different denominations, as afore stated, and to this end there is provided a plurality of separate pockets or coin chutes 25a, 26a and 27a arranged to receive a coin inserted in one of the slots 11, 12 and 13 respectively, the 45 coin engaging devices 25, 26 and 27 being associated respectively with said coin chutes 25a, 26a and 27a. Each of the coin chutes is adapted to receive a coin and to hold the same in a fixed position, as indicated in Figs. 7 and 50 8 of the drawings; and to this end each of said chutes is provided with a coin holding means comprising a plurality of spaced rollers 28 and 29 journalled in the side walls which define the coin receiving pocket or 55 chute, the said rollers forming a back-stop for the coin. The coin engaging device, such as 25, 26 or 27, associated with a coin chute, is arranged so as to normally project into the path of movement of a deposited coin, 60 as shown for example in Figs. 2 and 5 of the

drawings, and to intercept the coin, as most clearly shown in Figs. 2, 7 and 8 of the drawings. Thus when a coin such as 30 is inserted in a slot such as 11, it gravitates in the chute 25a and is intercepted by the roller 29 70 and the coin engaging device 25 (see Fig. 2) and is held between these parts ready for further operation. Any coin of smaller denomination than that intended for such chute 25a will fail to be intercepted and will fall 75 through into the deposit compartments C, and any coin larger than such denomination will either be prevented from being inserted by the size of the coin receiving slot such as 11, or by the rejecting operation of the registering 80 mechanism, as will be described hereinafter. It will be noted that the upper roller 28 is arranged in advance of the lower roller 29, thus functioning to prevent the return ejec- 85 tion of a coin of correct denomination. 90

The coin intercepting and engaging devices 25 to 27 comprise cam shaped elements forming a single unit and made for example out of a single blank of sheet metal shaped into the configuration best shown in Fig. 3 95 of the drawings; and the said unit, designated as 31, is mounted for a limited oscillating movement on a shaft 32 journalled in a U-shaped frame 33, which U-shaped frame is mounted for oscillating movement on a main spindle 34 which is journalled in the side walls of the casing A. The oscillating frame 33 is provided with the operating arm 17 heretofore referred to, which arm extends to the exterior of the casing A and is adapted to be manipulated for producing an oscillation of the frame 33 and the parts carried thereby between the positions shown in Figs. 2 and 8 of the drawings. Normally, the oscillatable frame is held in the position 100 shown in Figs. 1 and 2 of the drawings by means of a spring 35 coiled about the spindle 34 and having a point of application at the pin 36 fixed to a plate portion 37 of the frame 33. The coin intercepting unit 31 is also normally held in the position shown in Figs. 2 and 3 of the drawings by means of a spring 38 which is anchored at 39 to the U-shaped frame 33, and which has a point of application at and on a pin 40 fixed to one of the 110 coin engaging devices such as 27, this construction being best shown in Figs. 3 and 8 of the drawings. 115

The operating element 24 heretofore referred to preferably comprises a pawl element made preferably integrally with one of the coin engaging devices such as 25, the said pawl element 24 being normally out of engagement with and being adapted to be connected to a ratchet element 41 which is 120 fixed to the registering element or wheel 23. The ratchet element 41 and its attached wheel 23 are held against accidental movement by means of a stop and positioning pawl 42 mounted for pivotal movement on a second 125 130

spindle 43 journalled in the side walls of the casing A, the said pawl 42 being spring-held against the teeth of the ratchet wheel 41 by means of an extension 35a of the spring 35 having a part coiled about the spindle 43, all as most clearly shown in Figs. 3, 7 and 8 of the drawings.

With the construction thus far described, it will be seen that after a coin such as 30 is deposited into a chute such as 25a and is 5 intercepted by the roller 29 and the coin engaging device 25, the parts are in position for an operation of the registering mechanism. With the parts thus positioned, a depressing movement of the operating arm 17 causes the frame 33 to rotate on the spindle 34, and as a result of this movement of the frame 33, the coin engaging element 25 thereon performs in sequence three functions, 10 first, the fixed positioning of the coin 30 in its chute, second, the causing of the engagement between the operating pawl 24 and the operated ratchet 41, and third, the release of the coin from the chute after the registering element or wheel 23 has been moved the predetermined amount permitting the coin to drop or gravitate into the deposit compartment C. These functions are effected both 15 qualitatively and quantitatively by the cam 20 shape or configuration of the coin engaging device (25, 26 or 27) and by the positioning of the rollers 28 and 29 in the corresponding chute 25a, 26a or 27a. The fixed positioning of the coin is accomplished during the initial 25 or first part of the movement of the operating arm 17, such movement causing the coin engaging device, as for example 25, to force the coin 30 against the rollers 28 and 29, the advance spacing of the roller 28 preventing the 30 ejection of a coin of proper dimension from the chute. Continued movement of the operating arm 17 causes the cam-shaped device 25 to ride over the edge of the thus positioned coin, and said device 25 is actuated by its riding engagement over the coin 35 (against the action of the spring 38) for producing the operative connection between the pawl 24 and the ratchet wheel 41 and for driving said ratchet wheel 41 a distance predetermined by the configuration of the cam 40 face of said cam shaped coin engaging device 25. At a given point in the movement of the operating arm 17, the coin engaging device 25 terminates its travel over the edge of the 45 coin and the coin is then released and is free to move into the compartment C. As the ratchet wheel 41 is moved by the pawl 24, the holding pawl 42 is forced out of its holding position. The holding pawl 42 also functions 50 as a positioning pawl and to this end the number of teeth on the ratchet wheel 41 is made equal to or a simple multiple of the dial designations on the registering wheel 23.

This sequence of operations is shown in 55 Figs. 2, 7 and 8 of the drawings in connec-

tion with coins of different sizes or denominations, and a comparison of these figures as well as the sequence of operations shown thereby demonstrates the manner in which the degree of movement of the registering element such as the wheel 23 is predetermined and made to correspond with the size of the coin operated upon. By reference to these figures it will be seen that the coin engaging elements or devices 25, 23 and 27 are given different cam configurations, these devices being designed to produce different degrees of coin riding movements for the different sized coins. Thus, the device 25 will cause an operation of the registering wheel 41 to move the same an arc corresponding to a change from one designation to the next, while the coin engaging devices 26 and 27 will cause movements of said registering wheel 41 over arcs twice and five times the length of said first mentioned arc. In Fig. 2 of the drawings is shown the initial engagement between the device 25 and a coin in the chute 25a, and in Fig. 7 of the drawings is shown the riding engagement of the device 26 over a coin deposited in the chute 26a, while in Fig. 8 is shown the completion or end of the travel of the device 27 over a coin deposited in the chute 27a, the coin in said chute 27a being shown just prior to its release from said chute.

By means of this construction I am enabled to considerably simplify the number of elements and the law of operation of a registering bank of the character described. It will be noted that the construction permits the use of stationary chutes or pockets and the fixed positioning of the coins, thus eliminating the need for complicated mechanisms which operate upon the principle of coin movement. It will further be seen that a single operating pawl coordinated with a single ratchet wheel may be employed with the deposit of a coin of any of a large number of sizes, and a single unit such as 31 may be used in conjunction with all of the different sized coins. The registering mechanism therefore embodies a small number or a minimum of parts which may be made in few operations at a comparatively low cost.

The operated registering wheels may be made of any approved or well known design; and in the exemplification of the invention shown in the drawings, such registering wheels comprise an adding train formed of a plurality of wheels 23 and 23a, the former registering "cents" and the latter totaling "dollars", the wheel 23 being operated directly by the ratchet wheel 41 attached thereto and the wheel 23a being operated by the wheel 23 at each revolution of the latter. The means for actuating the wheel 23a by the wheel 23 may comprise any well known mechanism such as a star wheel and pinion 45 rotatable on the spindle 43, said star wheel and

70

125

130

pinion cooperating with the gear teeth 46 which may be struck out from the body of the wheel 23a, and with a toothed element 47 struck out from the body of the wheel 23 at a given point therein. The said wheel 23 is also grooved at its periphery as at 48 and provided with a recess 49 at the toothed section 47, these parts cooperating with the star wheel 45 to form a Geneva gear mechanism.

10 When the wheel 23 arrives at a position such as shown in Fig. 4 of the drawings, the toothed section 47 thereof engages a half tooth of the pinion 45 and moves said pinion a part of the revolution sufficient to cause the engagement between a full tooth thereof with gear teeth 46 of the wheel 23a and the toothed section 47 of the wheel 23, continued movements of the wheel 23 thereby causing a movement of the wheel 23a through the desired arc.

15 The use and operation of the registering bank of the present invention and the many advantages thereof will, in the main, be fully apparent from the above detailed description thereof. A coin is deposited in the appropriate chute and the operating key depressed, whereupon the indicated registration is increased to the new correct total, and the coin falls into the savings compartment. A plurality of coins should not be placed simultaneously in several chutes, as only the coin of higher value will be registered. When the registered total reaches a predetermined value, the door is opened and the savings may be removed.

20 35 While I have shown and described my invention in the preferred form, many changes and modifications may be made in the structure disclosed without departing from the spirit of the invention, defined in the following claims.

I claim:

1. In a coin registering mechanism, in combination, a registering element, a stationary coin chute adapted to receive a coin and to hold the same in fixed position, an operating element normally disconnected from said registering element, and means movable into engagement with and in riding contact over a coin manually deposited directly in said chute, said means being arranged so as to be actuated by its engagement with said coin for causing said operating element to become operatively connected to said registering element, and said means having a predetermined length of riding contact with said coin for predetermining the degree of movement of said registering element.

2. In a coin registering mechanism, in combination, a registering element, a stationary coin chute adapted to receive a coin and to hold the same in fixed position, a coin receptacle for receiving the coin when released from said chute, an operating element normally disconnected from said registering ele-

ment, a device positioned to intercept a coin deposited in said chute and movable into engagement with and in riding contact over said coin, said device being arranged so as to be actuated by its engagement with said coin for causing said operating element to become operatively connected to said registering element, and means for moving said device in riding contact over said coin, said coin being released from said chute at the end of such riding contact.

3. In a coin registering mechanism, in combination, a registering element, a stationary coin chute adapted to receive a coin deposited manually therein and to hold the same in fixed position, an operating element normally disconnected from said registering element and movable into engagement with a coin deposited in said chute, said operating element being arranged so as to be actuated during its engagement with said coin into operating connection with said registering element, and means for moving said operating element.

4. In a coin registering mechanism, in combination, a registering element, a plurality of stationary coin chutes adapted to selectively receive coins of different denominations and to hold a received coin in a given and fixed position, an operating element normally disconnected from said registering element, and means movable into engagement with a coin deposited in one of said chutes, said means being arranged to be actuated by its engagement with said coin for causing said operating element to become operatively connected to said registering element, the length of moving engagement between said means and each coin of different denomination being commensurately arranged to determine the extent of the operative connection between the operating element and the registering element, and hence the degree of movement of said registering element.

5. In a coin registering mechanism, in combination, a registering element, a plurality of stationary coin chutes adapted to selectively receive coins of different denominations and to hold a received coin in a fixed position depending upon the denomination, an operating element normally disconnected from said registering element, and means having a plurality of devices spaced to correspond to said positions and movable into engagement with a coin deposited in a corresponding one of said chutes, each of said devices being arranged to be actuated by its engagement with said coin for causing said operating element to become operatively connected to said registering element, the length of moving engagement between a device and a coin being arranged to determine the extent of the operative connection between said operating element and said registering element, and hence the degree of movement of said registering element.

6. In a coin registering mechanism, in combination, a registering element, a plurality of stationary coin chutes adapted to selectively receive coins of different denominations and including a plurality of pockets each for holding a received coin of a given denomination in fixed position, an operating element normally disconnected from said registering element, and means having a plurality of devices spaced to correspond to the said pockets and movable into engagement with a coin deposited in a corresponding one of said chutes, each of said devices being arranged to be actuated by its engagement with said coin for causing said operating element to become operatively connected to said registering element, the length of moving engagement between a device and a coin being arranged to determine the extent of the operative connection between said operating element and said registering element, and hence the degree of movement of said registering element, the length of such moving engagement with the coins being different for the coins of different denominations.

7. In a coin registering mechanism, in combination, a registering element, a stationary coin chute adapted to receive a coin and to hold the same in fixed position, an operating element normally unconnected to said registering element, a device connected to said operating element projecting into said chute and positioned to intercept a coin deposited therein, means for moving said device into riding engagement over said coin, the movement of said device against and over said coin causing first the fixed positioning of a coin in the chute and then an actuation of said device by the fixed coin to effect an operative connection between said operating element and said registering element.

8. In a coin registering mechanism, in combination, a registering element, a stationary coin chute adapted to receive a coin and to hold the same in fixed position, an operating element normally unconnected to said registering element, a device connected to said operating element projecting into said chute and positioned to intercept a coin deposited therein, means for moving said device into riding engagement over said coin, the movement of said device against and over said coin causing first the fixed positioning of a coin in the chute and then an actuation of said device by the fixed coin to effect an operative connection between said operating element and said registering element, the said device having a construction to provide a predetermined length of travel and a release of the coin from the chute at the end of such travel.

9. In a coin registering mechanism, in combination, a registering element, a stationary coin chute adapted to receive a coin and to hold the same in fixed position, an oscillat-

able frame, a coin intercepting and engaging device movably mounted on said frame, an operating element connected to said device and normally unconnected to said registering element, and means for oscillating said frame, oscillation of said frame in the presence of a coin in said chute causing riding engagement between said device and said coin and actuation of said device by said coin for effecting an operative connection between said operating element and said registering element.

10. In a coin registering mechanism, in combination, a registering element, a stationary coin chute adapted to receive a coin and to hold the same in fixed position, an oscillatable frame, a coin intercepting and engaging cam device movably mounted on said frame, an operating element connected to said cam device and normally unconnected to said registering element, and means for oscillating said frame, the said cam device having cam shaped sections such that oscillation of said frame in the presence of a coin in said chute causes riding engagement between said device and said coin to fix the position of the coin in the chute and then an actuation of said device by said coin to effect a driving connection between said operating element and said registering element.

11. In a coin registering mechanism, in combination, a registering element, a stationary coin chute adapted to receive a coin and to hold the same in fixed position, an oscillatable frame, a coin intercepting and engaging cam device movably mounted on said frame, an operating element connected to said device and normally unconnected to said registering element, and means for oscillating said frame, the said cam device being shaped so that oscillation of said frame in the presence of a coin in said chute causes first an actuation of said device by said coin effecting a driving connection between said operating element and said registering element, and then a release of the coin from said chute and a resulting release of said driving connection.

12. In a coin registering mechanism, in combination, a registering wheel, a ratchet wheel for driving the registering wheel, a stationary coin chute for receiving and holding a coin in fixed position, an operating pawl normally unconnected to said driving ratchet, a cam-shaped coin intercepting and engaging device connected to said pawl, and means for moving said device into engagement with and in riding engagement over a coin in said chute, the said device being mounted so that the engagement thereof with a coin in the chute actuates the said device to cause a continuous operative connection between said pawl and ratchet so long as said device is in engagement with the coin.

13. In a coin registering mechanism, in combination, a registering wheel, a ratchet wheel for driving the registering wheel, a stationary coin chute for receiving and holding a coin in fixed position, an operating pawl normally unconnected to said driving ratchet, an oscillatable frame, a cam-shaped coin intercepting and engaging device connected to said pawl and movably mounted on said frame, and means for oscillating said frame, oscillation of said frame causing a movement of said device into engagement with and in riding engagement over a coin in said chute, the engagement of said device with a coin in the chute actuating the said device to cause a continuous operative connection between said pawl and ratchet so long as said device is in engagement with the coin.

14. In a coin registering mechanism, in combination, a registering element, a plurality of stationary coin chutes adapted to selectively receive coins of different denominations and to hold a received coin in a given and fixed position, an oscillatable frame, a plurality of coin intercepting and engaging devices mounted as a unit on said frame for limited motion thereon, each of said devices being associated with one of said chutes, an operating element connected to said devices and normally unconnected to said registering element, and means for oscillating said frame, oscillation of said frame in the presence of a coin in one of said chutes causing an actuation of a device by said coin effecting a driving connection between said operating element and said registering element, the length of moving engagement between a device and a coin being arranged to determine the extent of the operative connection between the operating element and the registering element.

15. In a coin registering mechanism, in combination, a registering element, a driving ratchet therefor, a plurality of stationary coin chutes adapted to selectively receive coins of different denominations and to hold a received coin in a given and fixed position, an oscillatable frame, a plurality of coin intercepting and engaging cam devices mounted as a unit on said frame for limited motion thereon, each of said devices being associated with one of said chutes, an operating pawl element connected to said devices and normally unconnected to said driving ratchet, and means for oscillating said frame, oscillation of said frame in the presence of a coin in one of said chutes causing an actuation of a cam device by said coin effecting a driving connection between said pawl and ratchet, the length of moving engagement between a cam device and a coin being arranged to determine the extent or length of the operative connection between the pawl and ratchet.

Signed at Girard, in the county of Erie and State of Pennsylvania this 19th day of March, A. D. 1928.

STANLEY L. CONNELL.
